UNITED STATES PATENT OFFICE

MICHELE AUTERI, OF MILAN, ITALY, ASSIGNOR TO SIEMENS & HALSKE AKTIEN-
GESELLSCHAFT, WERNERWERK, OF SIEMENSSTADT, NEAR BERLIN, GERMANY

COIN-COLLECTING APPARATUS

Application filed November 11, 1926, Serial No. 147,687, and in Italy April 5, 1926.

The invention relates to a coin collecting apparatus for subscribers' stations in telephone systems, particularly of the automatic kind, in which the inserted coin is directed 5 by means of a movable coin chute either into the cash receptacle or into a refund chute leading outside, the coin serving at the same time as a medium for operating various contacts.

10 The known coin collecting apparatus of this kind depend on the weight of the inserted coin which must not be too small to bring about the switching operations necessary for actuating the contacts. The invention aims at producing a definite function 15 of the device, independent of the weight of the coin, this being done in that the movable coin chute is also used for controlling contacts for electrical switching operations.

20 According to the invention the arrangement is so contrived that the inserted coin is used as a coupling member for the tripping plunger of the movable coin chute for the purpose of displacing the same.

25 In the collecting position the coin chute is held by means of a special switching member which, during the transposition of the coin chute, gets into a locked position and during the insertion of the next coin in the 30 slot, it is again released from its locking position by the pressure exerted by the coin.

The drawing shows the invention by way of an actual example, several views being shown with all the unessential parts omitted.

35 Fig. 1 shows a plan view of the coin collecting apparatus with the casing removed and in its rest position.

Fig. 2 shows the coin collector in side elevation with the casing partly in section, the operating plunger being shown in two different positions.

Fig. 3 shows the apparatus in the same view with the plunger in the coin collecting position.

40 In the drawings, the sheet metal casing of the coin collecting apparatus is indicated by 1; 2 represents the cash receptacle arranged at the bottom of the casing, and 3 is the slot for the coin insertion. The opening 45 of the latter passes into a stationary

tubular portion 4 secured to the casing 1. A rotatably mounted lever 5 protrudes laterally into the tubular chute portion 4. This lever is provided at one end with an extension 6 which in the effective position of the 55 lever, as will be described later, acts upon contact springs 8 which are arranged laterally to the tubular portion 4 through the medium of swinging chute 7. Beneath the portion 4 there is a tubular coin chute portion 60 7 which, however, is not rigidly connected to the other tubular portion, but is movably mounted thereon by means of a leaf spring 9. By means of an extension 10 it closes a cut-away portion at one side of the upper 65 tubular portion 4.

The movable chute portion 7 has arranged beneath it the cash receptacle 2, the opening of which is continued as a chute 11 up to the bottom of the chute 7. However, as Fig. 2 70 shows, it does not enter right into the tube 7 but terminates somewhat to one side of it. 12 indicates the tubular portion running from the chute 7 to the coin refund opening 13. This portion 12 is formed of the sheet metal 14 of the chute 4, and connected to the casing 1 by means of the angular member 15. Movable mounted to the latter is a reciprocating plunger 16. One end of this plunger passes through openings 22 at the touching 75 faces of the chutes 7 and 12 and passes into the latter, where it is held by the tension of a spring 18. This end is provided with a shoulder portion 23, having a projecting end 24, which, in conjunction with the lower part 20 of the refund chute, serves as a stop for an inserted coin. The outwardly protruding end of the operating plunger 16 is provided with a ring 17 for easier manipulation. The method of operating the coin collecting apparatus will now be described in detail.

Upon inserting a coin 19 in the slot 3, and provided that the lever 5 is in the effective position, (Fig. 3), this depending upon whether the coin for the last insertion was cashed or not, the lever 5 is moved out of this position by the pressure of the coin; consequently the projection 6 of the lever releases the movable coin chute 7 so that it assumes the position as shown in Fig. 2. The coin now drops from 90 95 100

the stationary chute 4 into the movable chute 7, and is held at the bottom opening thereof upon the extension 20 of the refund chute 12, by the projecting end 24 of the plunger 16. 5 By the shifting of the lever 5 and the consequent movement of the chute 7, the contacts of the spring assembly 8 are operated by extension 10 of chute 7 to short-circuit the microphone, in known manner, and to remove 10 the short-circuit from the impulse springs of the number dial to render the number dial operable to establish the connection. The springs 8 are a set of three make and break springs arranged to open the shunt around the microphone and close a shunt around the calling device when chute 7 is in the position shown in Fig. 3, and to reverse 15 the condition of these circuits when the chute 7 is in the position shown in Fig. 2. 20 When the connection is established and the desired subscriber has answered, then, for the purpose of collecting the coin, the plunger 16 is pushed in so that the shouldered end 23 may enter the opening 22 of the chute, as 25 shown in Fig. 3, and come against the coin located therein, thereby moving the chute. Consequently, this chute 7 is placed in an oblique position (Fig. 3) permitting end 6 of the lever 5 to fall behind portion 10 of the 30 chute, so that the latter is held in this position. If the plunger 16 is again released, then, under the influence of one of its other springs 21 it returns to normal position. Now the coin 19 can drop into the tubular portion 11 of the cash box 2, as the neck 11 of said box is now beneath the opening of the 35 chute 7. Owing to the position of the chute 7, the short circuit of the microphone is again removed by the extension 10 of chute 7, so 40 that the conversation may take place.

If, however, the desired subscriber has not replied, or if he is already holding a conversation with another subscriber, then, the operating plunger 16 is drawn outward instead 45 of being pushed in. By this action the coin 19 is released, so that it slips from its supporting surface 20, through the obliquely arranged chute 12 to the return opening 13. An actuation of the contacts does not take place 50 in this case, as the position of the movable chute 7 remains unaltered. The plunger 16 is in this case returned to normal mid position by spring 18.

Now if, for the purpose of obtaining another call where the coin of the previous call was refunded, a coin is again inserted in the slot 3, this coin drops directly from the chute 4 into the chute 7, and remains there lying on the supporting face 20, because, owing to the 55 position of the lever 5, the short circuiting of the impulse contact of the number dial has already been removed by the extension 10. Thus, the connection can be established directly by setting the switch. According as 60 to whether the call to the desired subscriber

is put through or not, the coin is either collected or refunded by pulling or pushing the operating plunger 16.

An abuse of the coin collecting apparatus cannot take place on account of its construction, as the actuation of the contacts for the connection is only possible when a coin is inserted. Further, as the weight of the coin has no influence in this arrangement on the switching of the contacts, this being done entirely by the coupling member, the arrangement may be employed to advantage when small coins are to be used. It should be observed that, instead of only a single operating plunger for refunding and cashing the coin, two plungers may be provided, one of them serving to collect the coin, while the other one directs the coin to the refund opening when a connection is not successively established.

What is claimed is:

1. In a pay-station coin box, a stationary coin chute, a collecting receptacle, a refund receptacle, said stationary chute terminating in a movable chute for directing an inserted coin either into said collecting receptacle or into said refund receptacle, a plunger for arresting said coin and for moving said movable chute through the medium of said coin, a set of contact springs for performing electrical switching operations, and means on said movable chute for controlling said springs.

2. In a pay-station coin box, a stationary coin chute, a collecting receptacle, a refund receptacle, said stationary chute terminating in a movable coin chute for directing an inserted coin either into said collecting receptacle or into said refund receptacle, means cooperating with an inserted coin as a coupling member and for holding said coin in that position for displacing said movable chute to direct said coin into said collecting receptacle, a set of contact springs for performing electrical switching operations, and means on said movable chute for controlling said contacts.

3. In a pay-station coin box, a stationary coin chute, a collecting receptacle, a refund receptacle, said stationary chute terminating in a movable coin chute provided for directing an inserted coin either into said collecting receptacle or into said refund receptacle, manually controlled means cooperating with said inserted coin as a coupling member for arresting said coin and displacing said movable coin chute to collect said coin, a set of contact springs for performing the electrical switching operations, and means on said movable coin chute for controlling said contact springs.

4. In a pay-station coin box, a stationary coin chute, a collecting receptacle, a refund receptacle, said stationary coin chute terminating in a movable coin chute provided for directing an inserted coin either into said col-

lecting receptacle or into said refund receptacle, contact springs for controlling electrical switching operations, subscriber control means cooperating with a coin in said movable chute for operating said movable coin chute into the collecting position to operate said contact springs, and locking means on said stationary chute for maintaining said movable coin chute in said position to maintain said contact springs operated.

5. In a pay-station coin box, a stationary coin chute, a collecting receptacle, a refund receptacle, said stationary coin chute terminating in a movable coin chute provided for directing an inserted coin either into said collecting receptacle or into said refund receptacle, means for holding said coin and cooperating therewith as a coupling member for operating said movable coin chute into the 10 collecting position, means on said stationary chute for locking said movable coin chute in said position, a set of contact springs arranged to perform electrical switching operations, and means on said movable coin chute 15 for actuating said springs.

6. In a pay-station coin box, a stationary coin chute, a collecting receptacle, a refund receptacle, said stationary coin chute terminating in a movable coin chute provided for directing an inserted coin either into said collecting receptacle or into said refund receptacle, means cooperating with said inserted coin for moving said movable coin chute into the collecting position, means for locking 20 said movable coin chute in said position, said locking means operable by a coin subsequently inserted into said stationary coin chute for releasing said removable coin chute, a set of contact springs to perform electrical switching operations, and means on said movable coin chute 25 for controlling said springs.

7. In a pay-station coin box, a stationary coin chute, a collecting receptacle, a refund receptacle, said stationary coin chute terminating in a movable coin chute provided for directing an inserted coin either into said collecting receptacle or into said refund receptacle, a single operating member for arresting said coin and cooperating therewith 30 as a coupling member for controlling the operation of said movable coin chute, a set of contact springs provided to perform electrical switching operations, and means on said movable coin chute for controlling said 35 springs.

8. In a pay-station coin box, a stationary coin chute terminating in a movable coin chute, a collecting receptacle, a refund receptacle, a locking member in said stationary chute for locking said movable chute, contact springs for performing electrical switching operations, means on said movable chute for operating said contact springs when that chute is moved, a plunger adapted to be operated to move said movable chute, when it con-

70 tains a coin, to position it opposite said collecting receptacle and to allow said locking member to engage said movable chute, means for restoring said plunger to permit the coin to enter said collecting receptacle, said locking member operated by the next coin inserted in said stationary chute to unlock said movable chute and to permit the release of said contact springs, and means on said plunger for arresting said next inserted coin 75 in said movable chute.

In witness whereof, I hereunto subscribe my name this 12th day of October, A. D. 1926.

ING. MICHELE AUTERI.
